4 Claims. (Cl. 128—142)

This invention relates to breathing apparatus and more particularly to an arrangement whereby the likelihood of over-pressurization of a breathing mask is greatly reduced.

In prior devices of this type, a conduit was used to connect an oxygen regulator with the oronasal cavity of a breathing mask. The mask was provided with an inlet check valve and balanced exhalation valve which led back to a relief valve in the conduit and was subject to the pressure in the conduit. Inhalation by the user would cause opening of the inlet valve and closing of the exhalation valve. Upon exhalation by the user, the unbalanced pressure created would cause the inlet check valve to close and the exhalation valve to open. This would create an increased pressure in the conduit and if the pressure became too great, the relief valve situated therein would operate to expel the excess pressure.

However, if the inlet check valve developed a leak, pressure could not be built up across the check valve and accordingly, pressure could not be built up across the exhalation valve and the user was thereby prevented from exhaling.

Also, if the regulator was subject to leakage, the pressure upstream of the check valve would build up continuously and prevent the proper pressure differential across the check valve. If the regulator were to fail to open, the rear of the exhalation valve would be subject to high pressure. In either case, breathing would be impaired and danger of lung damage to the user would result.

Therefore, it is an object of this invention to reduce the possibility of excessive mask pressure in a breathing apparatus.

It is another object of this invention to eliminate an inlet check valve on the mask of a breathing apparatus.

In the preferred embodiment of this invention, a fluid pressure regulator is connected to a face mask and controls the fluid flow thereto from a source of fluid under pressure. A differential pressure operated exhalation valve is provided on the face mask and means is provided for subjecting one side of the exhalation valve to a predetermined pressure to insure operation of the valve regardless of the operation of the regulator, thereby preventing lung damage upon regulator failure and eliminating the use of an inlet check valve in the mask.

Other objects and advantages will become apparent from the following detailed description taken in connection with the accompanying drawings wherein:

FIG. 1 is a schematic illustration of a breathing apparatus;

FIG. 2 is a plan view of the regulator valve shown in FIG. 1, but on an enlarged scale;

FIG. 3 is a sectional view taken along line III—III of FIG. 2;

FIG. 4 is a sectional view taken along line IV—IV of FIG. 2 and having a small cut-away portion; and

FIG. 5 is a schematic illustration of the regulator mask connection on a reduced scale.

Referring more particularly to FIG. 1, the breathing apparatus includes a pressure reducing valve 10 connected to a suitable source of oxygen under pressure (not shown) by a conduit 12. The reducing valve 10 may be of any suitable form and serves to deliver oxygen at

2

a workable pressure to a breathing regulator 14 by means of a conduit 16. The regulator 14 is here shown as mounted on a face mask 18.

Referring now more particularly to FIGS. 2, 3, and 4, the regulator valve 14 comprises a casing 20 having a hollow tubular inlet fitting 22 extending from one side thereof. The casing 20 is also provided with an externally threaded lower portion 24, on which a nut 26 is carried. A wall 27 of face mask 18 is compressed between nut 26 and casing 20 to secure the casing 20 to the face mask 18. The inlet fitting 22 is adapted for connection to the conduit 16 (FIG. 1).

The inlet fitting 22 has a suitable filter 28 mounted therein, and is connected by means of a passage 30 to a valve chamber 32 formed within the casing 20. The valve chamber 32 communicates with the face mask 18 by means of a plurality of ports 34 which communicate with an opening 36 in the bottom wall of the casing portion 24.

20 An annular valve seat 38 is formed on the casing 20 within the valve chamber 32 for cooperation with a flexible diaphragm valve member 40 for controlling fluid flow from the inlet passage 30 to the ports 34. The valve member 40 is secured at its periphery to the wall of the casing 25 20 by means of an annular retaining member 42 formed on the casing.

A passage 44 extends through the casing 20 from the inlet passage 30 and opens into the valve chamber 33 on the lower side of the diaphragm valve member 40 to subject the lower side of the diaphragm valve member 40 to inlet fluid pressure. The passage 44 is provided with a chamber 46 in which a fitting 48 having a metering orifice therein is positioned. With this arrangement, the upper side of the valve member 40 is subjected to the inlet fluid pressure within chamber 30, and the lower side of the valve member 40 is subjected to the inlet fluid pressure by means of passage 44.

It will be apparent that the effective area of the valve member 40 exposed to the inlet fluid pressure at the lower side thereof is greater than the exposed area of the upper side. This difference in area subjected to inlet fluid pressure accordingly establishes a force differential on the valve member 40 which normally tends to hold the same in engagement with the seat 38.

45 The valve member 40 is moved out of engagement with the seat 38 to permit flow of fluid to the ports 34 and face mask 18 by venting the fluid pressure acting on the lower side thereof to reverse the force differential acting on the valve member 40. To this end, a passage 50 formed in the casing 20 extends from the valve chamber 33 at the underside of the diaphragm valve member 40 and opens into a chamber 52 formed in the casing 20 which communicates with the interior of the mask 18 by means of a port 54.

55 A flexible diaphragm sensing element 56 is secured at its periphery to the upper end of the casing 20 to enclose the chamber 52 and to define the upper wall thereof. The position of the diaphragm sensing element 56 is influenced by the fluid pressure within the chamber 52.

60 Accordingly, the chamber 52 is in communication with the mask 18, a reduction in the pressure will occur within the chamber 52 when the user of the apparatus inhales causing the diaphragm 56 to flex downward. This movement of the diaphragm 56 in response to inhalation by the user is used to control the venting of the fluid pressure acting on the underside of the valve member 40 to thus control opening of the valve member 40.

65 A hollow fitting 58 has one end pressed within the end of the passage 50 and the other end thereof projecting within the chamber 52 to define a pilot valve seat. A pilot valve, indicated generally by the reference

numeral 60, is cooperative with the end of the fitting 58 to control fluid flow from the valve chamber 33 through the passage 59 to the chamber 52. The pilot valve 60 comprises a rigid lever arm 62 having one end engageable with the diaphragm 56 and the other end thereof fixed to a block 64 overlying the fitting 58. One end of a strip 66 of sealing material is secured to the underside of the block 64 and the other end of the strip 66 is clamped to an extending and movable partition 68 of the casing 20 by means of a nut 70 tightened against the partition 68 by a screw 72 seated within a counterbore 73 in the casing portion 24. A spring 74 has one end attached to the block 64 and the other end thereof attached to the nut 70 for biasing the block 64 downwardly and the end of the lever arm 62 into engagement with the diaphragm 56. During assembly, the screw 72 is tightened to cause downward deflection of the partition 68 until the strip 66 engages the end of the fitting 58.

The spring 74 normally biases the block 64 and the strip 66 into engagement with the end of the fitting 58. However, should the diaphragm 56 be flexed downwardly by reduction in pressure within the chamber 52 as a result of inhalation, displacement of the lever arm 62 will occur, and the spring 74 will yield adjacent the nut 70 against its bias and move the block 64 out of engagement with the fitting 58 to permit flow of fluid from the passage 59. When the user exhales, the pressure in chamber 52 will increase to move the diaphragm 56 upwardly and allow the bias of spring 74 to close the pilot valve 60 thus reestablishing the force differential on the valve member 40 causing the same to engage its seat 38.

It has been found that the chattering or vibration of the diaphragm valve member 40 sometimes occurs due to the rapid pressure changes in chamber 33 upon opening and closing of the pilot valve 60. To provide for a more gradual pressure build-up or relief on the underside of the diaphragm valve member 40 during operation of the pilot valve 60, a surge chamber 76 having a metering orifice 77 is provided in the casing portion 24 in communication with the passage 44. It will be apparent that upon flow of fluid from the valve chamber 33 as a result of opening of the pilot valve 60, the flow of fluid from the chamber 76 as determined by the metering orifice 77 will reduce the rate of pressure drop within the chamber 33. Likewise, the rate of pressure build-up within the chamber 33 will be decreased by the pressure build-up in the chamber 76 when the pilot valve 60 is closed.

When the regulator thus far described is used at high altitudes or under low atmospheric pressure conditions, it is desired to establish a predetermined pressure within the mask or helmet 18 independently of inhalation on the part of the user to provide pressure breathing. Accordingly, the regular valve is provided with means for maintaining a predetermined pressure within the mask or helmet 18 in accordance with the surrounding atmospheric pressure. To this end, a cup-shaped member 78 having an upper inwardly extending flange 80 is clamped to the upper end of the casing 20 and to the periphery of the diaphragm 56 by means of a cover 82 threaded on the upper end of the casing 20 in engagement with a lower outwardly extending flange 81 of the member 78. The flange 80 is provided with a central bore 84 in which a cup-shaped valve member 86 is positioned. The valve member 86 is provided with an outwardly extending flange 88 terminating in an annular downwardly bent lip 90 above the flange 80.

The valve member 86, member 78 and diaphragm 56 define a chamber 92 above the diaphragm 56 which communicates with the inlet passage 30 by any suitable means, such as a restricted orifice 94. The orifice 94 thus establishes a fluid flow into chamber 92 which acts on the upper side of the diaphragm 56 through a plu-

rality of ports 95 in the bottom wall of the member 78.

The valve member 86 is cooperative with the flange 80 to control the fluid pressure within the chamber 92. When the valve member 86 is in the position shown in FIG. 3, the lip 90 is out of engagement with the flange 80 and fluid pressure is vented from the chamber 92 to the atmosphere through a plurality of ports 96 in the cover 82. However, if the valve member 86 is moved toward the diaphragm 56, the lip 90 will be moved closer to the flange 80 to throttle the flow of fluid from the chamber 92 and increase the fluid pressure in the chamber 92.

An expandable bellows member 97 is provided for actuating the valve member 86 relative to the flange 80. The bellows member 97 has one end sealed to the bottom wall of the valve member 86 and the other end thereof sealed to the flange 98 of a cup-shaped member 100. The member 100 is provided with a central conical recess or indentation 102 which engages a flange 104 formed on one end of a screw 106 threaded through the cover 82 in axial alignment with the bellows member 97. A spring 108 is mounted in compression between the valve member 86 and the flange 98 within the bellows member 97 and serves to bias the bellows member 97 and valve member 86 downward.

The bellows member 97 is evacuated and will expand in response to a decrease in atmospheric pressure to actuate the valve member 86 downward to move the lip 90 toward the flange 80. Thus, the bellows member 97 will expand in response to an increase in altitude to move the lip 90 toward engagement with the flange 80 to increase the fluid pressure within chamber 92.

Referring more particularly to FIG. 5, the oxygen regulator 14 is connected to the mask 18 in direct communication with oronasal cavity 114. A pressure differential operated exhalation or outlet valve 116 is provided on the mask 18 and has one side in communication with a passage 118, formed by any suitable piping, and the other side subject to the pressure within the oronasal cavity 114. The piping which forms passage 118 is connected to a fitting 120 (FIG. 3) which is connected to a passage 122 formed in the casing 20 of the regulator and the fitting 120 extends through the mask wall 27. A suitable seal 124 is provided to form a leak-proof connection between the fitting 120 and the mask wall 27. Another passage 126, which extends perpendicular to passage 122 and communicates therewith is connected to chamber 92 through ports 95. Therefore, one side of the exhalation valve 116 is subjected to the pressure within chamber 92 by way of ports 95, passages 126, 122, fitting 120, and passage 118.

A relief valve, indicated generally by reference numeral 128, is positioned adjacent the regulator 14 on the inlet side thereof to vent fluid pressure from passage 122 when the fluid pressure exceeds a predetermined value. To this end, a hollow tubular casing 130 is secured to casing 20 and is provided with a plurality of ports 132 extending through the wall thereof. A valve seating ring 134 is fixed within the tubular casing 130 and is adapted to be engaged by a valve member 136 which is slidably mounted on a guide stem 140 fixed to the end wall of the casing 130. A spring 138 encircles the stem and is mounted in compression between the end wall of the casing 130 and the valve member 136 for biasing the valve member 136 into engagement with the seating ring 134.

It will be apparent that a pressure differential will exist across the valve member 136 when the same engages the seat therefor since one side of the valve member 136 is subjected to the oxygen pressure within the passage 122 and the other side thereof is subjected to atmospheric pressure. As long as the pressure differential force on the valve member 136 is less than the bias of the spring 138, the valve member 136 will engage the seat. If, however, due to an increase in the fluid pressure in the

passage 122, the pressure differential force becomes greater than the biasing force of the spring 138, the valve member 136 will be moved out of engagement with the seat to vent the excessive fluid pressure in passage 122 to the atmosphere. This will allow the exhalation valve 116 to relieve excess mask pressure.

In operation, when the apparatus is used at low altitudes or at relatively normal atmospheric conditions, the bellows member 97 will be in the contracted condition and the valve member 86 will be in its uppermost position wherein the lip 90 is out of engagement with the flange 80. In this position of the valve member 86, fluid pressure is vented from the chamber 92 to the atmosphere, and the fluid pressure within the chamber 92 will be minimum and approximately atmospheric.

When the user of the apparatus inhales, a reduction in fluid pressure within chamber 52 will occur and the diaphragm 56 will be deflected downward under the influence of the fluid pressure within chamber 92. Such movement of the diaphragm 56 will cause opening of the pilot valve 60 as previously described to effect opening of valve member 40. When the valve member 40 is thus opened, oxygen will be supplied to the mask 18.

Since the chamber 52 communicates with the interior of the mask 18 by means of the port 54, exhalation on the part of the user will increase the fluid pressure within the chamber 52 to return the diaphragm 56 to its original position and allow bias of spring 74 to close pilot valve 60 and valve member 40.

If a decrease in atmospheric pressure should occur, such as during an increase in altitude, the bellows member 97 will expand to move the valve member 86 downwardly. This movement of valve member 86 will accordingly position the lip 90 closer to the flange 80 to throttle the flow of fluid from the chamber 91 causing an increase in fluid pressure within the chamber 92.

The increased fluid pressure in chamber 92 will move the diaphragm 56 downwardly and open the pilot valve 60 to effect opening of the valve member 40 to cause oxygen flow to the mask 18. However, since the chamber 52 is in communication with the mask, the supply of oxygen to the mask when the user is not inhaling will increase the pressure in chamber 52 causing a pressure force to be exerted on the diaphragm 56 in opposition to the fluid pressure acting on the upper side of the diaphragm 56. This build-up in the pressure within chamber 52 will continue until the pressure in chamber 52 equals the pressure in chamber 92 at which point the diaphragm 56 will have returned to its original position and allow the bias of spring 74 to close the pilot valve 60 and valve member 40.

It will be apparent that in operation in the above manner, the diaphragm 56 serves as a pressure regulator to maintain a fluid pressure within the mask 18 as determined by the position of the bellows member 97. Also, since inhalation on the part of the user is effective to open the pilot valve 60 by establishing a pressure differential on the diaphragm 56, it will be apparent that the sensitivity of the device to inhalation is constant irrespective of the atmospheric pressure condition sensed by the bellows member 97. This constant sensitivity is due to the fact that the fluid pressure in chambers 52, 92 is always substantially the same. Accordingly, when the user inhales, a similar pressure difference is established across the diaphragm 56 at pressure breathing conditions as is established at straight demand conditions. Thus, the device is operative to effect pressure breathing at low atmospheric pressure conditions without effecting the sensitivity of the device to inhalation and exhalation on the part of the user.

If it is desired to calibrate the response of the bellows member 97 to a particular atmospheric pressure condition, the screw 106 may be rotated to vary the axial position of the bellows member 97 and the valve member 86 relative to the flange 80. Such positioning of the bellows

member 97 will accordingly vary the pressure condition at which the lip 90 engages the flange 80.

Since the oxygen regulator 14 is in direct communication with the oronasal cavity 114 of mask 18 and no inlet check valve is utilized, it is obvious that over-pressurization of the face mask 18 due to failure of an inlet check valve is eliminated. Also, since the pressure differential operated exhalation valve 116 is subject to the pressure in chamber 92 which is controlled by aneroid valve member 86, breathing is not impaired by the exhalation valve due to a regulator leakage or failure on the downstream side thereof. Accordingly, failure of the regulator valve member 40 will not over-pressurize the face mask 18 and no lung damage will result therefrom. The only failure that could cause excessive mask pressure in this instance would be that which causes excessive pressure build-up in the chamber 92 and this is limited by relief valve 128.

It is now apparent that the present apparatus has eliminated the use of an inlet check valve and reduced the likelihood of over-pressurization of a face mask, thus accomplishing the objects of the present application.

While a single embodiment of this invention has been herein shown and described, it is apparent to those skilled in the art that many changes may be made in the construction and arrangement of parts without departing from the scope of the invention as defined in the appended claims.

We claim:

- 30 1. In a breathing apparatus for supplying fluid from a source of fluid under pressure to a cavity in a breathing mask or the like; a hollow casing, a flexible diaphragm dividing the interior of said casing into a first chamber communicating with said cavity and a second chamber vented to the atmosphere, inlet means on said casing adapted to be connected to said source of fluid under pressure, means in said casing defining a main passage and a pilot passage, both of said passages communicating at one end with said inlet means and at their respective other ends with said first chamber, valve means in said main passage responsive to pressure in said pilot passage to open said main passage to permit the flow of fluid therethrough from said inlet means to said first chamber only when the pressure at the inlet end of said main passage exceeds the pressure in said pilot passage by a selected pressure, normally closed pilot valve means in said pilot passage controlling the flow of fluid from said pilot passage into said first chamber, means for opening said pilot valve means in response to flexing movement of said diaphragm induced by a reduction in pressure in said first chamber to a selected pressure differential below the pressure in said second chamber, restricted orifice means in said casing placing said second chamber in constant communication with said inlet means, ambient atmospheric pressure responsive means for regulating the rate of venting of said second chamber in inverse proportion to the ambient atmospheric pressure, and means for venting said cavity when the pressure in said cavity exceeds the pressure in said second chamber.
- 40 2. Apparatus as defined in claim 1 wherein said means for venting said cavity comprises a differential pressure actuated valve member having a first side exposed to the pressure within said cavity, conduit means connecting the opposite side of said valve member to said second chamber, and pressure responsive relief valve means connected in said conduit between said second chamber and said differential pressure actuated valve member.
- 50 3. Apparatus as defined in claim 1 wherein said valve means in said main passage comprises means defining an annular valve seat having a central passage therethrough in communication with said inlet means, a valve port disposed outwardly of said valve seat and communicating with said first chamber, a flexible diaphragm valve mem-

70 ber mounted in said casing for movement into and out of

engagement with said valve seat and operable when engaged with said valve seat to block communication between said central passage and said port, said pilot passage having an enlarged chamber therein having one wall defined by said diaphragm valve member, the area of said diaphragm valve member exposed to said enlarged chamber being greater than the area of said central passage surrounded by said annular valve seat.

4. Apparatus as defined in claim 3 further comprising

means defining a surge chamber in said pilot passage between said inlet and said enlarged chamber.
